US0D1057543S

(12) **United States Design Patent** (10) **Patent No.:** **US D1,057,543 S**
(45) **Date of Patent:** **** Jan. 14, 2025**

(54) **ILLUMINATABLE SELECTOR LEVER ELEMENT**

(71) Applicant: **BattleArms IP, LLC**, Henderson, NV (US)

(72) Inventor: **George Huang**, Henderson, NV (US)

(73) Assignee: **BattleArms IP, LLC**, Henderson, NV (US)

(**) Term: **15 Years**

(21) Appl. No.: **29/746,792**

(22) Filed: **Aug. 17, 2020**

Related U.S. Application Data

(60) Continuation-in-part of application No. 16/735,161, filed on Jan. 6, 2020, now Pat. No. 10,746,489, and a continuation-in-part of application No. 29/600,620, filed on Apr. 13, 2017, now Pat. No. Des. 904,854, and a continuation-in-part of application No. 29/586,078, filed on Nov. 30, 2016, now Pat. No. Des. 896,610, said application No. 29/600,620 is a division of application No. 29/491,527, filed on May 22, 2014, now Pat. No. Des. 786,649, said application No. 29/586,078 is a continuation of application No. (Continued)

(57) **CLAIM**

The ornamental design for an illuminatable selector lever element, as shown and described.

DESCRIPTION

FIG. 1 is a right, rear, upper perspective view of an illuminatable selector lever element, showing my new design; FIG. 2 is a left, rear, upper perspective view thereof; FIG. 3 is a right, front, upper perspective view thereof; FIG. 4 is a left, front, upper perspective view thereof; FIG. 5 is a right side view thereof; FIG. 6 is a left side view thereof; FIG. 7 is a top view thereof; FIG. 8 is a bottom view thereof; FIG. 9 is a front view thereof; and, FIG. 10 is a rear view thereof.

The broken lines shown throughout the various figures depict additional structures that form no part of the claimed design.

1 Claim, 5 Drawing Sheets

Related U.S. Application Data

29/491,527, filed on May 22, 2014, now Pat. No. Des. 786,649, which is a continuation-in-part of application No. 13/068,287, filed on May 7, 2011, now Pat. No. 8,806,790.
